(57) **CLAIM**

The ornamental design for a controller cable, as shown and described.

DESCRIPTION

FIG. 1 is a front, top, and right side perspective view of a first embodiment of a controller cable;

FIG. 2 is a front, bottom, and left side perspective view thereof;

FIG. 3 is a rear, top, and right side perspective view thereof;

FIG. 4 is a rear, bottom, and left side perspective view thereof;

FIG. 5 is a top plan view thereof;

FIG. 6 is a bottom plan view thereof;

FIG. 7 is a front elevational view thereof;

FIG. 8 is a rear elevational view thereof;

FIG. 9 is a left side elevational view thereof; and,

FIG. 10 is a right side elevational view thereof.

The broken lines in the drawings showing portions of the controller cable are included for the purpose of illustrating environmental structure and form no part of the claimed design.

1 Claim, 10 Drawing Sheets
